CONTROL SYSTEM

Application filed September 30, 1927. Serial No. 223,012.

My invention relates to motor-control systems and it has particular relation to control systems for use with elevators, hoists and similar machinery.

5 An object of my invention is to provide a control system for motors used with machinery designed to operate between a plurality of points of travel, wherein the motor may be automatically controlled to stop, 10 the machine accurately at such predetermined points.

Another object of my invention is to provide a control system for elevators wherein the elevator may be automatically stopped 15 accurately level with the several floors which it serves.

A further object of my invention is to provide a control system for automatically stopping elevators accurately level with the 20 floors, wherein the mechanism for achieving such accurate stopping may be located at a point remote from the floor.

Another object of my invention is to provide a control system for stopping elevators 25 accurately with the floors which is readily adaptable for use with elevators having different numbers of accelerating speeds.

My invention will be described with reference to the accompanying drawings, where- 30 in:

Figure 1 is a diagrammatic view of a control system for an elevator using my automatic stopping mechanism;

Fig. 2 is a plan view of the switch used to 35 effect the automatic stopping, and

Fig. 3 is a view, in end elevation, of the switch illustrated in Fig. 2.

Referring to Fig. 1, the control system 40 therein shown for a single elevator comprises an elevator car C suspended by a cable Ca, which passes over a hoisting drum D to a suitable counterweight (not shown) as is customary. The hoisting drum D is directly coupled to a hoisting motor EM, which is 45 illustrated as of the shunt-wound type. The control for the motor EM is of the vari-volt or Ward-Leonard type, wherein a driving motor M, of the shunt-wound type, comprising armature M' and shunt field winding MF, has its armature M' directly coupled to

the armature G' of a generator G. The generator G is of the variable-voltage compound-wound type, comprising an armature G', a series field winding GSF, a shunt field winding GF and a demagnetizing field winding GAF. The armature G' of the generator G is connected in "loop" circuit with the armature EM' of the hoisting motor EM. The motor EM is shown as having its field winding EMF connected directly across the supply lines L1 and L2.

The elevator motor EM is controlled, in the usual manner, through the agency of a car switch CS on the car, the usual control actuating devices "up" and "down" direction switches designated as 1 and 2, respectively, and a series of speed switches 3, 4 and 5.

The apparatus may best be described with reference to an assumed operation. Assuming the elevator to be at the first floor, the attendant on the car may start the car upwardly by movement of the handle 10 of the car switch CS to the left, thus completing a circuit for the up-direction switch 1 extending from line conductor L1, through conductors 11 and 12, normally closed contact members a of the "down"-direction switch 2, conductor 13, the coil of up-direction switch 1, conductor 14, contact members 15, 16 and 17 of the car switch CS and conductor 18 to line conductor L2.

The up-direction switch 1 closes its contact members b and c, thus supplying the generator shunt field winding GF with current in one direction, by way of a circuit which extends from line conductor L1, through conductors 11 and 19, contact members b on up direction switch 1, conductor 20, resistors 21, 22 and 23, conductor 24, generator shunt field winding GF, conductors 25 and 26, contact members c on up direction switch 1, and conductor 28 to line conductor L2. The generator thus supplies voltage in one direction to the elevator-motor armature EM', causing the elevator motor EM to move the car upwardly.

As the car switch CS is moved farther to the left, the contact member 16 is brought into co-operation with contact members 30, 100

31 and 32 to successively complete circuits to the actuating coils of speed relays 3, 4 and 5, which relays, in turn, successively short-circuit the resistors 23, 22 and 21 to increase the current supplied to the generator 5 shunt field winding GF and to cause the consequent acceleration of the elevator motor EM.

The circuit for the speed relay 3 extends from line conductor L1, through conductors 10 11 and 19, to a contact brush 33 of a slow-down and stopping switch S, (the construction and purpose of which is hereinafter described). Thence, the circuit continues 15 through a contact ring 48, a contact brush 35, conductor 36, the coil of speed relay 3, conductor 37, contact members 30, 16 and 17, of the car switch CS, and conductor 18 to line conductor L2. The circuits for the speed 20 relays 4 and 5 may be similarly traced through contact brushes 38 and 39, respectively, of two other contact rings on the slow-down switch S.

The slow-down switch S comprises a base 25 40 (Fig. 2) upon which is mounted a normally inactive shaft member 41 supported in suitable bearings 42 and 43. The bearings are secured to the base 40 by attaching screws, such as shown at 44. Fixed near one 30 end of the shaft 41 is a gear-wheel 45 for driving the shaft 41. A series of contact rings, designated by the numerals 46, 47, 48 and 49, respectively, are suitably supported upon insulating discs 50, 51, 52 and 53, respectively, which are fixed to the shaft 41 in spaced relation. As may readily be seen by an inspection of Figs. 1 and 2, the contact ring 49 extends substantially throughout a 35 complete circle, there being only a short arcuate gap between the ends of the ring. The contact rings 48, 47 and 46 extend successively through lesser portions of a complete circle.

Each of the contact rings has associated 45 therewith a pair of contact brushes mounted upon opposite sides of the shaft 41, the brushes coacting with the contact ring 49 being designated by the characters 55 and 55', those for cooperation with the contact 50 ring 48 being designated as 33 and 35, those coacting with the contact ring 47 being designated as 38 and 38' and those cooperating with the contact ring 46 being designated as 39 and 39'. The effect of the successively 55 shortened length of the contact members 49, 48, 47 and 46 is such that the rotation of the shaft 41, by movement of the gear-wheel 45, will cause the successive breaking of contact between the brushes cooperating with 60 the contact rings 46, 47, 48 and 49, in the order stated.

A shaft member 56 is suitably supported upon the base 40 by means of bearing members 57 and 58, and has fixed thereon a 65 sprocket-wheel 59. A sleeve 60 keyed to the

shaft 56 for rotation therewith but longitudinally movable with reference to the shaft 56, carries a suitable spur gear-wheel 61 for engagement with the gear-wheel 45 on the shaft 41. A suitable helical spring 62, acting between the gear-wheel 61 and the face of a magnet coil 63, forces the spur gear-wheel 61 and the sleeve 60 to the left upon the shaft 56, to normally maintain the gear-wheels 45 and 61 out of engagement. The gear-wheels 61 and 45 thus constitute a clutch for coupling the shafts 41 and 56 for movement in correspondence with movements of the elevator.

The sleeve 60 is constructed of suitable magnetic material and constitutes the movable core for a clutch-operating solenoid, the energizing coil 63 for which is fixed to the base 40 by a suitable bracket 64. The sprocket-wheel 59 is suitably connected, in any well-known manner, to some part of the driving or operating mechanism for the elevator, for example, as by a chain 65, to thus impart to the sprocket-wheel 59 a movement which is in correspondence with the movements of the elevator up and down its shaft.

Referring to Fig. 1, this chain 65 is represented as an endless chain which extends from a point of attachment to the elevator car, designated as 66, downwardly to a sheave 67 at the lowermost portion of the hatchway and thence upwardly over the sprocket-wheel 59 and back to the point of attachment 66. In this manner, the sprocket-wheel 59 and the spur gear-wheel 61 will always move in correspondence with the movements of the elevator, regardless of stretching of the elevator cables or slippage between the cable and the hoisting drum D.

The operation of this slow-down switch S is such that the energization of the magnet coil 63 will draw the gear-wheel 61 into engagement with the gear-wheel 45, causing the motion of the elevator car C to be transmitted to the several contact rings 46, etc., and thus 110 causing movements of the contact rings to correspond to farther movement of the elevator car C. When the coil 63 is deenergized, the spring 62 will move the gear-wheels 45 and 61 out of engagement and permit a spring 115 68 to restore the shaft 41 and the contact rings to normal position. It should be noted that the same effect may be produced by having the spring 62 maintain the gear-wheels in engagement and having the magnet 63 120 disengage them when the car is running at high speed.

Each of the "up" and "down" direction switches 1 and 2 and of the speed relays 3, 4 and 5 is provided with a self-holding circuit 125 that is closed by the actuation of the associated switch or relay. From an inspection of Fig. 1, it will be seen that the holding circuits for the switches lead through the respective contact rings on the slow-down 130

- switch S. The holding circuit for the up-direction switch 1 extends from line conductor L1, through conductors 11 and 12, contact member *a* on down-direction switch 2, conductor 13, coil of up-direction switch 1, conductors 14 and 70, contact members *d* on up-direction switch 1, conductors 71 and 72, brushes 55 and 55' and the contact ring 49 of the slow-down switch S, and conductors 73 and 74 to line conductor L2. The holding circuits for each of the speed relays 3, 4 and 5 will not be traced, but it is apparent from a casual inspection of Fig. 1 that the holding circuit for the speed relay 3 extends through the contact ring 48; the holding circuit for the speed relay 4 extends through the contact ring 47, and the holding circuit for the speed relay 5 extends through the contact ring 46.
- Assuming, for example, that the elevator car C is to stop level with the second floor, represented by the dotted line designated "2nd", the attendant upon the car will center the car switch CS some time prior to the arrival of the car at the second floor. Through the operation of suitable inductor relays, designated as 75, for the "up" direction, and designated as 76 for the "down" direction, which relays may be of the type disclosed in the copending application of John F. Clancy, Serial No. 559,997, filed May 11, 1922, or in the copending application of Harold W. Williams, Serial No. 190,482, filed May 11, 1927, (both applications being assigned to the Westinghouse Electric and Manufacturing Company), a circuit will be completed for energizing the magnet coil 63 of the slow-down switches when the car is a predetermined distance away from the second floor level.
- The circuit for the inductor relay 75 extends from line conductor L1, through conductors 11 and 19, contact members *f* on up-direction switch 1, conductor 77, the coil of relay 75, conductors 78 and 79, contact members 80, 16 and 17, and conductor 18 to line conductor L2. Thus, as the inductor relay passes its cooperating magnetizable iron plate 81, suitably mounted in the hatchway, the relay 75 will close its contact members 82 to complete the circuit for the clutch coil 63, which circuit extends from line conductor L1, through conductor 11, the coil 63, conductors 83 and 84, contact members 82, and conductors 85 and 18 to line conductor L2. At this instant, the energization of coil 63 will cause engagement of the gear-wheels 61 and 45, and further movement of the car C will be transmitted to the contact rings 46, etc.
- As the car C continues upwardly past the inductor plate 81, a slight rotation of the shaft 41 of the slow-down switch S will cause the contact ring 46 to move from engagement with the contact brush 39', thereby opening the circuit to the speed relay 5. Speed relay 5 opens its contact members to re-insert the resistor 21 in circuit with the generator shunt field winding GF, thus slowing down the elevator motor EM. Further movement of the car C will, in like manner, deenergize the relays 4 and 3, successively, to reinsert the resistors 22 and 23 in circuit with the generator shunt field winding GF and cause further slowing down of the motor EM.
- After the car C has travelled a predetermined distance past the inductor plate 81, such distance being sufficient to bring the car level with the floor, the ratio between the gear-wheels 61 and 45 is such that the shaft 41 will have moved through a sufficient distance to move the contact ring 49 out of engagement with the contact brush 55', thus breaking the holding circuit for the up-direction-switch 1. The consequent deenergization of the up-direction-switch 1 causes the car to stop at such time as it is substantially level with the second floor.
- By proper designing of the gear-wheels 61 and 45, and properly determining the length of the respective contact rings 46, etc., the car may be made to stop level with the floor with extreme accuracy.
- It will be noted that, with my system, an elevator car may have its movements completely controlled in an automatic manner without the necessity of mechanical contact between the car and the hatchway, as is necessary in the use of cams and rollers and similar devices. Moreover, a large number of slow-down steps, represented by the resistors 21, 22, etc., may be incorporated in an elevator control system using my slow-down switch, by the mere addition of a greater number of contact rings and discs on the slow-down switch shaft 41.
- The use of the slow-down switch S, located remote from the elevator car C, also removes an objection to existing automatic controlling devices for elevators in that there is no necessity for mounting a large quantity of apparatus on the car structure. However, should it be desired to mount the switch S on the car, the only change required would be that of attaching the chain to the top and bottom of the shaft in place of the attachment to the car.
- It has not been deemed necessary to describe the operation of the relays and circuit when the elevator is travelling in the down direction, it being obvious that the operation is the same, with the exception that, in this instance, the contact rings 46, etc. are moved from engagement with the contact brushes 39, 38, 33, and 55, the effective slow-down and stopping of the elevator being accomplished in the same manner as described for the up direction.
- While I have shown the final stopping of the elevator as controlled by the slow-down

switch S, it is obvious that the final stop may be accomplished by other means; for example, by a second inductor-relay device similar to those designated 75 and 76, or by a floor-selector device also actuated by the chain 65 as is described in Reissue Patent No. 17,097, to M. Baruch, dated October 9, 1928. Also the energization of the magnet 63 at the proper time may be accomplished in many ways other than by the inductor-relay device shown; for example, by contact members on a floor-selector, such as is commonly used for elevator signal systems.

The embodiment of my invention described is merely illustrative, and I do not desire to be limited to the details of the apparatus disclosed, except as defined in the appended claims.

I claim as my invention:

1. In a control system for elevators, motive means for said elevator, means for actuating said motive means to determine the direction and speed of movement of said elevator, means for controlling said actuating means to slow down and stop said elevator, and means driven in correspondence to movements to said elevator engageable with said controlling means when said elevator arrives at predetermined points in its travel, for actuating said controlling means to slow down and stop said elevator accurately at other predetermined points in its travel.

2. In a control system for elevators, motive means for said elevator, means for actuating said motive means to drive said elevator at a high speed and a plurality of intermediate speeds, means for controlling said actuating means to slow down said elevator from high speed to stop in a series of successive steps of diminishing speed, and means driven in correspondence to movements of said elevator engageable with said controlling means when said elevator arrives at predetermined points in its travel for actuating said controlling means to slow down and stop said elevator accurately at other predetermined points in its travel.

3. In a control system for an elevator operable past a floor-multi-speed motive means for said elevator, control means for starting and accelerating said elevator through successive steps of increasing speed, normally inactive means for actuating said control means to decelerate and stop said elevator, means operable in correspondence to movements of said elevator and means operably dependent upon the approach of said elevator to a predetermined distance from said floor for engaging said actuating means and said moveable means to slow down and stop said elevator level with said floor.

4. In a control system for elevators having a plurality of actuatable devices for operating said elevator at different speeds, means for

actuating said devices, means for maintaining said devices active when actuated, means for releasing said actuatable device comprising a normally inactive member, a member movable in correspondence to movements of said elevator, and means for coupling said members for simultaneous movement when said elevator arrives at predetermined points in its travel.

5. In a control system for elevators, having a plurality of actuatable devices for operating said elevator at different speeds, electro-responsive means for actuating said devices, self-holding means for maintaining said devices when actuated, means for releasing said actuatable devices comprising a normally inactive member, a member movable in correspondence to movements of said elevator, and means for coupling said members for simultaneous movement when said elevator arrives at predetermined points in its travel.

6. In a control system for elevators, having a plurality of actuatable devices for operating said elevator at different speeds, means for actuating said devices, means for maintaining said devices active when actuated, means for progressively releasing said actuatable devices to slow down and stop said elevator in steps of progressively diminishing speed, said releasing means comprising a normally inactive member, a member movable in correspondence to movements of said elevator; and means for coupling said members for simultaneous movement when said elevator arrives at predetermined points in its travel.

7. In a stop motion switch for elevators, a movable shaft, a plurality of contact members, means actuated by movement of said shaft for successively actuating said contact members, means movable in correspondence to movements of said elevator, means operable to couple said movable means and said shaft to move said shaft in correspondence to movements of said elevator from a normal position to an abnormal position, and means normally biasing said shaft to said normal position.

8. In a stop-motion switch for elevators, a shaft movable from a normal position to an abnormal position, means movable in correspondence to movements of said elevator, means operable to couple said movable means and said shaft to move said shaft in correspondence to movements of said elevator, a plurality of normally closed switching devices for controlling the movements of said elevator, and means on said shaft for successively actuating said switches to open-circuit condition on movement of said shaft to abnormal position.

9. In a stop-motion switch for elevators, a shaft movable from a normal position to an abnormal position, means movable in correspondence with movements of said elevator, magnetic means operable to couple said mov-

able means and said shaft to move said shaft in correspondence to movements of said elevator, a plurality of normally-closed switching devices for controlling the movements of said elevator, and means on said shaft for successively actuating said switches to open-circuit condition on movement of said shaft to abnormal position.

- 5 10. In a control system for elevators operable past a floor, motive means for said elevator, means for controlling the direction and speed of said elevator including an up-direction switch, a down-direction switch and a plurality of speed switches, means for actuating said speed switches and for selectively actuating either of said direction switches to cause said car to move at the highest speed, means for maintaining said switches closed when actuated, means movable from a normal position to an abnormal position for successively opening the active speed and direction switches to slow down and stop said elevator in steps of progressively diminished speed, and means operable when said car arrives at 15 20 25 30 35 40 45 50 a predetermined distance from said floor for coupling said movable means to said elevator for movement in correspondence to the movements of said elevator to thereby stop said elevator accurately at said floor.
11. In a control system for elevators operable past a floor, motive means for said elevator, means for controlling the direction and speed of said elevator, including an up-direction switch, a down-direction switch and a plurality of speed switches, means for actuating said speed switches and for selectively actuating either of said direction switches to cause said car to move at the highest speed, means for maintaining said switches closed when actuated, means movable from a normal position to an abnormal position for successively opening the active speed and direction switches to slow down and stop said elevator in steps of progressively diminished speed, means operable when said car arrives at a predetermined distance from said floor for coupling said movable means to said elevator for movement in correspondence to the movements of said elevator to thereby stop said elevator accurately at said floor, and means for returning said movable means to normal position.

In testimony whereof, I have hereunto subscribed my name this 19th day of Aug. 1927.

55 RAY P. HIGBEE.
